CANDLESTICK

John M. Powers, Cleveland Heights, Ohio

Application November 10, 1937, Serial No. 173,801

15 Claims.

(Cl. 67—27)

This invention relates to automatically actuated candlesticks adapted for use upon church altars etc. Candlesticks of this type generally embody a tubular false candle housing constructed and decorated to simulate a candle and mechanism within the housing for automatically feeding an actual candle upwardly within the housing against a suitable stop means in such a fashion that the wick of the candle and the flame arising therefrom extend above the upper end of the candle housing and produce the effect of a never shortening burning candle. As well known, proper burning of devices of the above described character, that is burning of a candlestick with a proper flame and without running over of melted wax, depends entirely upon length of the exposed end of the candle wick which controls the size of the flame and therewith the amount of wax melted at the top of the candle, and on alignment of the flame with the axis of the candle body effecting symmetrical heating and melting of the wax at the upper end of the candle. Presently known candles and candlestick structures do not satisfy these requirements for proper burning of a candle or candlestick, mainly, because these requirements oppose each other. Thus the length of the exposed wick end of a candle can be controlled only by specific wick construction giving the wick the tendency to bend its upper end when burning, and bending of the wick end of a candle effects lateral shifting of the candle flame and therewith unsymmetrical heating and melting of wax at the top of the candle. Such unsymmetrical heating of a candle effects dripping of the candle and interferes with proper action of the feeding mechanism of the candlestick by wax dripped upon the moving parts of such mechanism.

It is the primary object of this invention to wholly obviate these drawbacks in present day candlesticks by providing an automatically actuated candlestick with a durable, stable, incombustible wick structure which extends a short distance downwardly into the top of candle-like wickless wax body, the latter being in a customary manner fed upwardly within a housing against an individual seating centering and stop means.

Another object of the invention is the provision of an automatically actuated candlestick with a stationary incombustible wick structure embodying a heat conducting base portion including heat conducting supporting finger portions extending upwardly therefrom, and an in-

combustible wick mounted on said base portion.

A further object of the invention is the provision of an automatically actuated candlestick with a stationary incombustible wick structure embodying a heat conducting base portion having heat conducting supporting finger portions upwardly extended therefrom, an incombustible fibrous wick supported by said base portion and cap-like perforated cover means at the top of said wick.

Still another object of the invention is the provision of an automatically actuated candlestick with an incombustible wick structure including a wick of silicious, fibrous material such as spun glass, the fibers of which are mounted on a central post of heat conducting material.

A still further object of the invention is the provision of an automatically actuated candlestick with a specific current and heat insulating axially bored top member carrying in its axial bore an individual heat conducting seating and sealing member for a candle-like wax body, an incombustible wick structure including a silicious fibrous wick, and an electrical heating element adjacent to said wick to effect electrical igniting of the wick by current sent through the electrical heating element.

With the above and other incidental objects in view, the invention consists in certain novel features of construction and combination of parts, the essential elements of which are set forth in the appended claims; and a preferred form of embodiment of the invention is herein-after shown with reference to the drawings forming part of the specification.

In the drawings:

Fig. 1 is a longitudinal sectional view partly in elevation through an automatically actuated candlestick with an incombustible wick structure attached thereto.

Fig. 2 is an enlarged top view of the candlestick shown in Fig. 1.

Fig. 3 is a fragmentary enlarged sectional view through the upper portion of the candlestick, the section being taken on line 3—3 of Fig. 2.

Fig. 4 is a cross-sectional view on line 4—4 of Fig. 1.

Fig. 5 is a cross-sectional view on line 5—5 of Fig. 1.

Fig. 6 is a cross-sectional view on line 6—6 of Fig. 1.

Fig. 7 is a cross-sectional view on line 7—7 of Fig. 1.

Fig. 8 is a cross-sectional view on line 8—8 of Fig. 3.

Fig. 9 is a cross-sectional view on line 9—9 of Fig. 3.

5 Fig. 10 is a sectional view through the upper portion of the candlestick, the section being taken on line 10—10 of Fig. 2.

Fig. 11 is an assembly view of the stationary wick structure.

10 Figs. 12 through 16 show the individual parts of the wick structure shown in Fig. 11; thus

Fig. 12 is a sectional view through the cap,

Figs. 13 and 14 are side and cross-sectional views of the wick.

15 Fig. 15 is a sectional view partly in elevation of the supporting cup for the wick and

Fig. 16 is a sectional view partly in elevation of the supporting element for the supporting cup.

Referring now more particularly to the exem-

20 plified form of the candlestick shown in the drawings 2 designates a supporting base which

seats in its recessed bore 3 a candle shifting mech-

25 anism 4. This mechanism embodies a stationary lower member 5 and a shiftable upper member 6

associated and coupled with said lower member

by means of a pulley arrangement 7 mounted

on a U-shaped guide post 8 of lower member 5.

Upper member 6 slidably engages with its U-

shaped post 9 the guide post 8 of lower member

5, which post 9 supports at its upper end a candle

supporting platform 10 including a guide pin 11

upwardly extended from the recessed central area 12 of said platform. Pin 11 engages with

the recess 14 in the lower end of a candlelike wickless wax body 15 and thus properly aligns

35 the body 15 with the shifting mechanism. A counterweight 16, suspended from pulley wires or cords 17 of the pulley arrangement 7, forces

member 6 and body 15 upwardly into engagement

40 with a centering sealing and seating member 18 of a wick supporting cover structure 19, which latter is secured to a tubular, longitudinally slotted member 20 resting on lower portion

5 and sleeved into bore 3 of base 2. A tubular longitudinally slotted skirting member 21, deco-

45 rated to simulate a candle, rotatably seats upon base 2 and thus permits ready access to the candle shifting mechanism when a slot 22 in member

21 is brought into alignment with a similar slot

50 23 in the tubular member 20.

Preferably, as shown, lower member 5 carries

and supports two elongated small tubes 24 and

25, which tubes are arranged symmetrically within

55 tubular member 20 and extend through the

entire length of said member for a purpose later

to be described.

The top end of tubular member 20 supports the top or cover structure 19, mounting a permanent wick structure 28. Cover structure 19 is made of

60 heat and current insulating material such as fiber, glass, etc., and embodies a ring-shaped base portion 29, partly extended into tubular

65 member 20 and seated with its flange 30 upon the upper edge 31 thereof, and a ring-shaped top portion 32 rigidly secured to said base portion 29.

Top portion 32 of cover structure 19 is provided with oppositely arranged sleeve-like

70 extensions, an upper extension 34 and a lower extension 35, which latter snugly fits the inside

75 wall of bore 36 in base portion 29 when portions 29, 32 are assembled. Preferably, top portion 32 is recessed at its bottom face to form a ring-

shaped air circulating chamber 37 between as-

sembled portions 29 and 32. Air inlet and outlet

75 passages 38, 39 for chamber 37 insure proper

circulation of air therethrough. The lower ex-
tension 35 on top portion 32 seats the centering
sealing and seating member 18 and is counter-
sunk to provide a circular stop shoulder 40 for
said member, which is of double cone-shaped
form and engages the candlelike, wickless wax
body 15 yieldingly forced toward said member
by the shifting mechanism 4. Upper extension
34 of the cover structure 19 mounts the perma-
nent wick structure 28. This structure embodies
a tubular base and supporting portion 42 of heat
conducting material having rigidly attached
thereto two symmetrically arranged upwardly ex-
tended springing finger or arm portions 43, 44
which yieldingly engage a circular groove 45 in
the bore 46 of upper extension 34 and securely
suspend base and supporting portion 42 in the
cover structure 19. The portion 42 of the wick
structure carries a cup-shaped holder 47 of heat
conducting material which embodies an integral
downwardly extended stem 48 sleeved through
the tubular base portion 42. The side and bot-
tom walls of the holder 47 are perforated as at
50 and, in addition, slotted as at 51 to facilitate
entering of melted wax into the holder and pack-
ing material 52 arranged within said holder,
which material tightly grips a wick 53 of spun
glass 54 wound around and interengaged with a
wire core 55. The top portion of wick 53 carries
a cap or cover member 56 clamped to said wick
30 and provided at its upper end with openings
or slots 57.

The wick 53 draws melted wax similar to com-
monly used candle wicks and feeds the necessary
amount of wax to the flame of the candlestick. 35
In addition, the wick structure automatically
controls the amount of wax melted at the top of
the wax body 15 by means of the upwardly ex-
tended finger or arm portions 43, 44. These arm
portions, when freely exposed, are directly heated 40
by radiation from the flame of the wick 53 and
transfer their heat through tubular portion 42
to the stem 48, which stem engages and is slightly
extended into the wax body 15. The heat
transferred to stem 48 effects melting of the wax 45
at the top of body 15 and when the amount of
wax melted is larger than the wax consumed by
the flame, then the melted wax begins to accu-
mulate in the upper extension 34 and while ris-
ing in said extension slowly covers the exposed 50
finger or arm portions 43, 44, thus reducing the
area of portions 43, 44 which is freely exposed to
the direct heat radiated from the flame. The
centering, seating and sealing member 18, which
perferably is made of heat conducting material,
has no direct contact with the wick structure 28
and does not effect direct melting of the wax
body 15 except shortly after the candlestick has
been lit. In this case, when all wax on wick 53
60 has been burnt off and the candle flame has
moved downwardly to the holder 47, the upper
portion of member 18 is fully exposed to the ra-
diating heat of the flame and directly effects
melting of the wax body 15. At this time wax
body 15 melts more rapidly and more wax is
65 melted than burnt by the flame. Consequently
the melted wax accumulates in the upper ex-
tension 34 and while slowly rising covers the
member 18, the holder 47 and part of the finger
70 portions 43, 44 until the melting of wax and its
consumption by the flame are in equilibrium.
In this state melted wax transfers sufficient heat
75 to the sealing member 18 to soften the wax en-
gaged therewith to permit of inward shifting of 75

the softened wax into the melting area controlled by stem 48 of the wick structure 28.

The described candlestick which is entirely automatically actuated and self adjusting may readily be refilled with a new wax body when slots 22 and 23 in members 21 and 20 respectively are brought into alignment by rotation of member 21 and when platform 10 is shifted downwardly without removal of the wax body 15 sticking to the sealing member 18. Such refilling and alignment of the refiller with the stumps of the old body 15 is facilitated by recessing the bottom of each body 15 and pointing its top.

Candlesticks of the type described are well adapted for co-operation with devices for lighting and extinguishing same, as the arrangements of parts and the use of a cover member of insulating material for the candlestick materially simplifies the use of electrical lighting means and extinguishing means. Such construction of a candlestick embodies the elongated small tubes 24, 25. The tube 24 is used to carry an insulated wire 58 with two current conducting leads 59, 59' and the tube 25 serves to carry a stream of air 25 to a blow-out nozzle 60 when a rubber ball, not shown, or any other similar device connected to said pipe is suddenly compressed, as will be clearly understood from an inspection of the drawings. The lower ends of lead wires 59, 59' may be readily connected to a source of current, not shown, and the upper ends of said wire leads are connected by means of spring contact members 64 to a heating and igniting coil 65 partly surrounding the wick 53 to more rapidly effect melting, vaporizing and igniting of the vapors of the wax.

Having thus described my invention, what I claim is:

1. In a candlestick a housing, shifting means adapted to vertically shift a candle-like body within said housing, a substantially ring-shaped cover member for said housing, ring-shaped heat conducting means supported by said cover member and downwardly extended therefrom for stopping, centering and sealing a candle-like body when carried upwardly by said shifting means, and an incombustible wick structure axially extended through said cover member and said stopping, centering and sealing member, said wick structure including heat conducting means mounting same on said cover member and extending said structure downwardly into said wax body for heat exchange therewith.

2. In a candlestick a housing, shifting means adapted to vertically shift a candle-like body within said housing, a substantially ring-shaped cover member of heat insulating material for said housing, ring-shaped heat conducting means mounted in said cover member and downwardly extended therefrom for stopping, centering and sealing a candle-like body when carried by said shifting means, and an incombustible wick structure axially extended through said cover member and said stopping, centering and sealing member, said wick structure including heat conducting means mounting same on said cover member and extending said structure downwardly into said wax body for heat exchange therewith.

3. In an automatically actuated candlestick having means for automatically shifting a candle-like wickless wax body upwardly against a stopping and sealing member, a ring-shaped top member and an incombustible wick structure supported by said top member and extended thereto, said wick structure including upwardly ex-

tended heat conducting arms arranged within said top member and downwardly extended heat conducting means extending fully through said top member.

4. A candlestick as described in claim 1, wherein said incombustible wick structure embodies a heat conducting base portion having upwardly inclined heat conducting means arranged within said cover member, and downwardly extended heat conducting means axially aligned with said cover member, and a wick portion of incombustible fibrous material supported by said base portion.

5. A candlestick as prescribed in claim 1, wherein said incombustible wick structure embodies a heat conducting base portion having a cup-shaped perforated body with upwardly inclined flattened arm portions and a downwardly extended stem substantially axially aligned with said cover member, and a wick portion of incombustible fibrous material supported in the perforated body of said base portion.

6. A candlestick as described in claim 2, wherein said incombustible wick structure embodies a heat conducting base portion adapted to centrally engage a candle-like wax body carried by and shifted by said shifting means upwardly against said ring-shaped stopping and centering means, and a wick portion of incombustible fibrous material mounted in said base portion, said wick portion including a heat conducting portion supporting said material.

7. A candlestick as described in claim 1, wherein said incombustible wick structure embodies a heat conducting base portion adapted to engage in heat exchanging contact with a candle-like, wickless wax body when shifted upwardly against said stopping, centering and sealing means, and a wick portion mounted in said base portion, said wick portion embodying a heat conducting member and spun glass engaged with and supported by said member.

8. A candlestick as described in claim 1, wherein said incombustible wick structure embodies a heat conducting base portion arranged within said top member, a wick portion of incombustible fibrous material supported in said base portion and perforated cap means secured to and covering the top end of said wick portion.

9. In a candlestick a tubular housing, a candle-like, wickless wax body within said housing, shifting means adapted to support and vertically shift said wax body, a substantially ring-shaped cover member of heat insulating material for said housing, ring-shaped means of heat conducting material mounted in said cover member for stopping upward movement of said body and centering and sealing the top end of said body with respect to said cover member, heat conducting supporting means for a permanent wick arranged centrally within said cover member, inclined upwardly extended attachment means on said supporting means for attaching same to said cover, downwardly extended heat transfer means adapted to engage the top of said wax body when shifted against said stopping means and a wick of incombustible fibrous material mounted in said supporting means and upwardly extended therefrom.

10. A candlestick comprising a tubular housing, a candle-like wickless wax body within said housing, shiftable supporting means for said wax body adapted to vertically shift said body in said housing, a substantially ring-shaped cover member of heat insulating material for

said housing, a cone-shaped ring means in said cover member adapted to stop upward movement of said wax body and fluid tightly seal its circumferential top edge to said cover member, a 5 heat conducting cup-shaped, perforated supporting member mounted within said cover member and provided with upwardly and downwardly extending heat transfer means, and an incombustible wick of fibrous material mounted in said cup-shaped supporting means, said upwardly extended heat transfer means being exposed to the 10 flame of said wick when ignited and said downwardly extended heat transfer means being extended through said cone-shaped means for heat exchange contact with said candle-like, wickless 15 wax body.

11. A candlestick as described in claim 10, wherein the ring-shaped body of said cover member is chambered and provided with inlet and 20 outlet passages to effect free air circulating through the chambered portion of said cover member.

12. In a candlestick a tubular housing, a candle-like, wickless wax body within said housing, shifting means for supporting and vertically shifting said wax body, a substantially ring-shaped cover member of insulating material for said housing, heat conducting stopping, centering and sealing means for said wax body mounted in the bottom portion of said cover member, an incombustible wick structure supported in the 25 top portion of said cover member and centrally extended therethrough, and an electrically actuated 30

heating and igniting coil for igniting said wick structure, said heating coil being directly attached to said cover.

13. A candlestick as described in claim 12, wherein said wick structure includes a wick of fibrous incombustible material, and wherein the 5 heating coil is vertically coiled partly around said wick.

14. An automatically actuated candlestick as described in claim 3, wherein said heat conducting upwardly extended arms are made of springing material adapted to frictionally engage the 10 inner wall of said ring-shaped top member for removably seating said wick structure in proper working position.

15. In a candlestick a tubular housing, a ring-shaped cover of insulating material secured to said housing, a restricted cone-shaped ring in the bottom portion of said cover, a carriage within said tubular housing capable of supporting a candle-like, wickless wax body between 20 said cone-shaped ring and said carriage, means urging said carriage toward said cone-shaped ring, an incombustible wick structure supported by said cover member and extended centrally 25 therethrough for heat exchange contact with a wickless wax body carried by said carriage, and an electric heating and ignition means directly secured to said cover and positioned adjacent to said wick structure for igniting the wax thereon 30 when electric current is passed through said igniting means.

JOHN M. POWERS.
